UNITED STATES PATENT OFFICE

GROSVENOR N. ALLEN AND MARY G. PARKER, OF ONEIDA, NEW YORK, ASSIGNEES TO ONEIDA COMMUNITY, LIMITED, OF ONEIDA, NEW YORK, A CORPORATION OF NEW YORK

DESIGN FOR A METAL BORDER STRIP

Application filed August 26, 1930. Serial No. 36,786. Term of patent 14 years.

To all whom it may concern:

Be it known that we, GROSVENOR N. ALLEN and MARY G. PARKER, citizens of the United States, residing at Oneida, county of Madison, State of New York, have invented a new, original, and ornamental Design for a Metal Border Strip fully described and represented in the following specification and the accompanying drawing, forming a part of the same, and showing a strip embodying the design.

In said drawings, Figure 1 is a front view of a metal border strip showing our new design, and Figures 2 and 3 are cross sections substantially on lines 2-2 and 3-3, respectively, of Figure 1.

We claim:

The ornamental design for a metal border strip substantially as shown.

In testimony whereof we have hereunto set our hands.

GROSVENOR N. ALLEN.
MARY G. PARKER.
